17 Claims. (Cl. 214—37)

1

This invention relates to blast furnaces and particularly to a method and apparatus for charging the furnace.

One method for charging a blast furnace, is to discharge a load of stock from a skip car into a small hopper, the bottom of which is closed off by a bell which can be lowered to discharge the stock into a larger hopper which in turn is closed off by a larger bell. As soon as the large hopper has received a half round of the stock, usually consisting of two skip car loads of coke, and one skip each of ore and stone, the large bell is opened and the stock is dropped into the furnace. Where two skip cars are used for hoisting the stock, one is hoisted to the top of the furnace on one track, while the empty car is lowered on the other track. Thus, the cars discharge their loads to one side or the other of the center of the furnace, there being a receiving hopper or chute for funneling the stock into the small hopper. This causes an off-center loading of the small hopper, thus resulting in an uneven stock charge onto the large bell, and a corresponding uneven distribution of stock in the furnace. Such uneven distribution is very undesirable.

A method heretofore used in an effort to eliminate the irregularity of distribution is to rotate the small bell and hopper as a unit a fixed number of degrees, after the stock has been dumped into it, and before the charge is dropped onto the large bell. The usual practice has been to rotate the hopper 60° for each dump of the small bell for one round of charge, 120° for the next, 180° for the next, 240° for the next, 300° for the next, and no movement for the next round. This distributes the uneven loading of the stock around the furnace at 6 points, and the equipment as a whole is thus usually referred to as a "6 point distributor."

Another method has been to utilize a single skip car which dumps its load into the center of the small hopper thus attempting to eliminate the side eccentricity of loading. The materials pouring out of the skip car, however, tend to load the small hopper higher on one side than on the other depending upon the nature of flow of the different materials which constitute the stock. The 6 point distributor, therefore, is customarily used with a single skip car in an effort to diminish or smooth out the uneven distribution.

Both of the foregoing methods do not provide a satisfactory even distribution but produce instead, what might be termed a uniformly irregular distribution, because of the fact that the un-

2

even loading of the stock on the small bell is distributed at 6 points in the furnace.

A third method of charging the furnace includes a construction by means of which the small bell and hopper are lifted as a unit from the top of the furnace and then lowered to the stock house adjacent the base of the furnace for filling. At the loading point, the bell and hopper are placed upon a table which is mounted upon a scale car, and as the hopper is being filled with stock from bins, the table is rotated. This method gives a more uniform distribution of stock in the furnace, but the necessity for raising and lowering the bell and hopper as a unit is so cumbersome and expensive that it is seldom used. A further objection is the fact that whenever the hopper is transported to the top of the furnace, it must be sealed so as to prevent undue escape of gas whenever the bell of the large hopper is lowered for discharging the contents thereof into the furnace. The problem of sealing the furnace, and at the same time permitting the hopper to be periodically removed when empty and repositioned when loaded has also been a serious objection to the use of such method.

One of the causes of unequal distribution is the difference in the physical characteristics of the various materials with which the furnace is charged. Such differences cause the different materials to vary in the path taken by them as they leave the skip car and pass through the receiving hopper or funnel. Thus, for example, a skip car will empty its load of coke in about four seconds, whereas the time required to discharge ore will vary from approximately three seconds to fourteen seconds. The moisture content in the ore is a factor in the time required for discharging it. Thus, a wet, sticky ore will cling to the car until it is tipped to a certain angle, whereupon the load slides quickly and nearly straight down the side of the receiving hopper. On the other hand, a dry, stony ore will leave the car more gradually and will require as high as 14 seconds to unload. Moreover, the dry ore will swirl around the receiving hopper during the dumping operation. Such irregularities, therefore, are repeated at each dumping operation.

An object of the present invention is to retain the inherent advantage of keeping the small hopper at the top of the furnace and of obtaining uniform distribution of stock within the furnace without encountering any of the objections hereinbefore set forth.

Briefly, the present invention contemplates the

rotation of the small hopper, together with its associated bell, substantially a complete revolution in the shortest period of time required for dumping any of the different materials utilized for charging the furnace. The invention contemplates a continuous rotation of such hopper during the dumping operation, and preferably an initiation of the rotation as the skip car approaches the top of the furnace. Thus, suitable time is permitted for accelerating the hopper and bringing it up to the desired speed by the time that the skip car is in position for dumping its load. The invention further preferably contemplates a stoppage of hopper rotation either after the skip car has been dumped, or after the small bell has been dumped, as desired.

Referring to the drawings, Fig. 1 is a vertical section of a furnace top and charging mechanism, to which our invention may be applied; Fig. 2 is a vertical section taken on a scale larger than that shown in Fig. 1, and illustrating the seal between the upper hopper and the body of the furnace; Fig. 3 is a vertical section taken on a scale larger than that in Fig. 2 and illustrating a driving mechanism for the upper or small hopper; Fig. 4 is a horizontal section taken on a plane indicated by the line 4—4 in Fig. 3; Fig. 5 is a schematic wiring or diagram for operation of the hopper driving motor when used with a single skip car, and Fig. 6 is a schematic wiring diagram for operating the hopper driving motor when two skip cars are used for charging the furnace.

Referring to Fig. 1, the dome of the blast furnace body is indicated at 10, at the top of which is shown a small bell 11, and a large bell 12, arranged in series with one another. The small bell is attached to the lower end of a tube 15, which is adapted to be raised and lowered by a hoisting mechanism (not shown) for raising and lowering the bell with respect to a small hopper 20. The large bell is attached to the lower end of a rod 21 which passes through the tube 15 and which is adapted to be raised and lowered by suitable hoisting mechanism (not completely shown). The large bell is thereby adapted to be raised and lowered with respect to a large hopper 25. Thus, the small bell normally holds the bottom of the hopper 20 closed, while the large bell holds the bottom of the hopper 25 closed.

Disposed above the hopper 20 is a receiving hopper or funnel 30 into which the contents of a skip car, indicated by the broken lines 31, may be dumped when the car reaches the top of an inclined trackway 32.

The present invention contemplates the rotation of the small hopper 20 and small bell 11, at least substantially a complete revolution, for the shortest period of time required for dumping a carload of material into the receiving funnel. Accordingly, the hopper 20 is mounted for rotation with respect to the body of the furnace, and is shown as having a laterally extending circular flange 33 to which is attached a ring gear 34, which is adapted to mesh with a pinion 35 on a shaft 36. The shaft is journalled in a suitable housing 37 and is adapted to be driven by a worm wheel 38 which meshes with the worm 39. The worm is fixed to a shaft 40 which is adapted to be driven by an electric motor 41. Thus, the hopper 20, and its associated bell 11, are rotated whenever the motor 41 is rotated.

The hopper 20 may be supported for rotation

upon spaced rollers 45, each of which is journalled in a bearing 46, the latter of which may be attached to the furnace body 10 by brackets 47. The rollers are adapted to engage an annular trackway 48 which is attached to a flange 50, the latter of which extends laterally from the upper end of a sleeve 51 and is in turn rigidly attached to the flange 33. Thus, the sleeve 51 rotates with the hopper and is disposed between the outer wall of the furnace body, and an inner concentric wall 55. In this way, the space between the walls 54 and 55 provides a receptacle 56 for holding water, whereas the bottom of the sleeve 51 terminates short of the bottom of the receptacle, whereby water may be introduced into the reservoir through a conduit 57 and withdrawn through a conduit 58, thus providing adequate circulation of water by means of which the receptacle 56 may be maintained full of water up to the level of the draw-off conduit 58 in order to seal the rotating hopper against leakage of gas from the furnace body.

In the ordinary operation of a furnace, the skip car will deliver one or more loads of ore, coke and stone in accordance with a predetermined charging plan, but the time required for dumping each load will vary, as previously stated, from approximately 3 seconds to 14 seconds. The present invention, therefore, contemplates the initiation of a rotation of the hopper 20 so as to bring it up to speed as the car approaches the top of the furnace. The invention additionally contemplates a continuous rotation of the hopper during the dumping operation, and at a rate of one complete revolution for substantially the shortest period of time required to dump any car load. Thus, for the example given, the hopper would be rotated 20 revolutions per minute, whereby the material being dumped in the shortest period of time will be uniformly distributed entirely around the hopper regardless of the order in which the material is brought to the top of the furnace, and regardless of the nature or condition of the material at the time of delivery to the furnace. The phrase "uniformly distributed" means that at the completion of each dumping operation, the material is substantially level in the rotating hopper.

The preferred method of operation is to rotate the hopper only during the dumping operation of the skip car, wherefore, provision is made for closing the circuit to the motor 41 as the car approaches the top of the incline and sufficiently in advance of the commencement of the dumping operation to permit acceleration of the hopper to the desired speed of rotation. One method of accomplishing this is to provide a switch in circuit with the motor and to actuate the switch by a member which is connected to the drum used for hoisting the skip car. A preferred manner of stopping the rotation of the motor at the completion of the dumping operation is to utilize a timer which is in circuit with the starting switch and motor, and which is set for stopping the motor in a predetermined number of seconds after the closing of the circuit. The timer is adjustable and can, therefore, be set to interrupt the motor circuit, as desired, by stopping the rotation of the hopper at the completion of the dumping operation. In practice the hopper may, if desired, be kept stationary for a sufficient length of time between movements of the skip car to permit lowering of the bell 11 for discharging the contents of the hopper 20, or may, if desired, be kept rotating until the hopper 20 is

discharged and the bell 61 is returned to the closed position.

The schematic wiring diagram of Fig. 5 is illustrative for an installation utilizing a single skip car, wherein the motor 41 may be supplied with current through lines L-4 and L-2, and may have, in its circuit, a starting switch, indicated at 60, and a stopping switch which is included in a timer, indicated in general at 61. The starting switch is biased to open position by a spring 62, whereas the stopping switch within the timer is biased to closed position. An operating member indicated at 60A may be moved in the direction indicated by the arrow 63 by rotation of the hoisting drum for the skip car in any suitable way. Thus, closing of the switch 60 causes a flow of current from the line L-4 through contactor 64, line 65, timer 61, line 66, motor 41, line 67 and back to line L-2. Closing of the circuit energizes a solenoid 68 through lines 69 and 70, thus operating to hold switch 60 closed until the circuit is opened by the timer. Opening of the circuit deenergizes the solenoid 68, thus allowing a spring 62 to move the switch 60 to the open position. In practice, the timer is adjusted to open the circuit after the maximum time required for any dumping operation, wherefore the motor rotates continuously at a rate equal at least to substantially one revolution for the minimum time required for any dumping operation. The opening of the circuit may be either at the end of the period of time required for the longest dumping operation or until after the contents of the rotating hopper have been dumped into the large hopper.

Where two cars are used for loading a furnace then a schematic wiring diagram suitable for operating a single motor is shown in Fig. 6 wherein parts corresponding to those of Fig. 5 are designated by the same reference characters. In Fig. 6, however, there is an additional starting switch 60, together with an additional solenoid 81. The same timer can be used, hence, whenever the member 60A is actuated during the movement of one car toward the top of the furnace, the circuit bearing the same reference characters as Fig. 5 would be operated in the same manner for actuating the motor 41. On the other hand, whenever the other car is moving toward the top of the furnace, the member 80A would operate to close the switch 80, whereupon the current flow at such time would be from line L-3 to contactor 82, switch 80, line 83, timer 61, line 66, motor 41, line 67 and back to line L-2. Energization of the timer also completes a circuit through line 84, solenoid 81 and line 85 to hold the switch 80 closed until the timer operates to open the motor circuit.

An advantage of the present invention is the fact that a uniform distribution of the material is attained. This is evidenced by the fact that depth tests made on a furnace operating in accordance with this invention, have shown a variation of only a few inches at the top of the charge in the furnace, whereas heretofore, the depth would vary at least a foot or more with any method of charging previously known to us. This minimizes the tendency of the gas to channel through the column of stock in the furnace and adds greatly to the life of the furnace lining, and quality of iron produced. A further advantage is that the even distribution has been an important factor in reducing the amount of flue dust emanating from the furnace. Thus, for example, it has been found that a furnace operating in accordance with this invention has

shown a reduction of flue dust from about 200 pounds per ton of iron to about 50 pounds per ton of iron. Such reduction has resulted in higher efficiency of furnace operation.

We claim:

1. A method of charging a blast furnace, wherein materials to be fed into the furnace are delivered to the top of the furnace in skip carload lots and are dumped into a hopper which is closed at the bottom by a movable bell, and wherein the time required for dumping any skip carload varies with the nature and physical conditions of the material, comprising rotating the hopper continuously from the time that the material commences to leave the car and until all of the material is dumped into the hopper, said rotation being at such speed that the hopper makes substantially one revolution during the time required for the fastest dumping operation of all of the materials to be fed into the furnace, whereby at the completion of each dumping of a skip car, the material in the rotating hopper is substantially level.

2. A method of charging a blast furnace with materials which are delivered to the top of the furnace in skip carload lots, and are dumped into a hopper which is closed at the bottom by a movable bell, wherein the time required for complete removal of the contents of each car, varies from approximately 3 to approximately 14 seconds, comprising rotating the hopper and bell as a unit continuously during the entire dumping operation of each skip carload, the speed of rotation being at least one revolution in approximately three seconds.

3. A method of charging a blast furnace wherein materials to be fed into the furnace are delivered to the top of it in skip carload lots and are dumped into a hopper which is closed at the bottom by a movable bell, and wherein the time required for dumping a skip carload varies with the nature and physical condition of the material, comprising initiating the rotation of the hopper and bell as a unit as the car approaches the top of the furnace, said initiation occurring sufficiently in advance of the arrival of the car at the top of the furnace to enable the hopper to be accelerated to uniform speed at the commencement of the dumping operation, maintaining a speed of rotation such that one complete revolution of the hopper is made for the fastest time in which the dumping operation can be performed, whereby at the completion of each dumping of a skip car, the material in the rotating hopper is substantially level and then stopping the rotation of the hopper within a predetermined period of time after the initiation of the hopper rotation.

4. A method of charging a blast furnace wherein materials to be fed into the furnace are delivered to the top of it in skip carload lots and are dumped into a hopper which is closed at the bottom by a movable bell, and wherein the time required for dumping a skip carload varies with the nature and physical condition of the material, comprising initiating the rotation of the hopper and bell as a unit as the car approaches the top of the furnace, said initiation occurring sufficiently in advance of the arrival of the car at the top of the furnace to enable the hopper to be accelerated to uniform speed at the commencement of the dumping operation, maintaining a speed of rotation such that one complete revolution of the hopper is made for the fastest time in which the dumping operation can be performed, whereby at the completion of each

dumping of a skip car, the material in the rotating hopper is substantially level and then stopping the rotation of the hopper after the car has been dumped.

5. A method of charging a blast furnace, wherein materials to be fed into the furnace are delivered to the top of it in skip carload lots and are dumped into a hopper which is closed at the bottom by a movable bell, there being two cars for each furnace, and so arranged that an empty car is moving downwardly while a loaded car is moving upwardly, and wherein the time required for dumping a skip carload lot varies with the nature and physical condition of the material, comprising rotating the hopper and its associated bell as a unit continuously during the entire dumping operation of each skip carload and at such speed that the hopper makes at least one revolution during the time required for the fastest dumping operation, initiating the rotation of the hopper sufficiently far in advance of the arrival of any car at the top of the furnace that the hopper may be accelerated to a uniform rate of speed by the time that the dumping operation commences, whereby at the completion of each dumping of the skip car, the material in the rotating hopper is substantially level and stopping the rotation of the hopper after each car has been dumped.

6. A method of charging a blast furnace, wherein materials to be fed into the furnace are delivered to the top of it in skip carload lots and are dumped into a hopper which is closed at the bottom by a movable bell, there being two cars for each furnace, and so arranged that an empty car is moving downwardly while a loaded car is moving upwardly, and wherein the time required for dumping a skip carload lot varies with the nature and physical condition of the material, comprising rotating the hopper and its associated bell as a unit continuously during the entire dumping operation of each skip carload and at such speed that the hopper makes at least one revolution during the time required for the fastest dumping operation, whereby at the completion of each dumping of a skip car, the material in the rotating hopper is substantially level, initiating the rotation of the hopper sufficiently far in advance of the arrival of any car at the top of the furnace that the hopper may be accelerated to a uniform rate of speed by the time that the dumping operation commences, stopping the rotation of the hopper after each car has been dumped and before the other car delivers a load to the furnace, and lowering the bell to discharge the load in the hopper while the hopper is stationary.

7. An apparatus for charging a blast furnace, comprising in combination, a furnace having a hopper and bell supported for rotation at the top thereof, a liquid seal between the hopper and the top, an electric motor connected to the hopper, a skip car, means for moving the skip car up an incline to deliver a load of material into the hopper, switch means in circuit with the motor for initiating the operation of it as the skip car approaches the top of the furnace, said switch means being actuated while the car is sufficiently far from the top of the furnace to allow the motor to accelerate to uniform speed by the time that the car reaches the top of the furnace, said uniform speed being at least one complete revolution of the hopper during the time required to empty the contents of the car into the hopper, whereby at the completion of

each dumping of a skip car, the material in the rotating hopper is substantially level.

8. An apparatus for charging a blast furnace, wherein materials to be fed into the furnace are delivered to the top of it in skip carload lots, and wherein the cars are dumped into a hopper which is closed by a movable bell, comprising in combination, means for rotating the hopper and bell as a unit at a speed substantially equal to one revolution for the time required for the material in any skip carload to start flowing from the car into the hopper and until the entire contents are discharged into the hopper, whereby at the completion of each dumping of a skip car the material in the rotating hopper is substantially level, an electric motor for rotating the hopper, switch means in circuit with said motor, said switch means being operated sufficiently in advance of the arrival of any car at the top of the furnace, that the hopper is accelerated to a uniform speed before the dumping operation starts, a second switch in circuit with said motor, timer means in circuit with said motor, and switch means responsive to the operation of said timer means for disconnecting the motor circuit within a predetermined period of time after the motor has been started.

9. In combination, a blast furnace, a material receiving hopper positioned at the top thereof, a movable bell closing the hopper, an electric motor for rotating the hopper, a source of current supply in circuit with the motor, a pair of skip cars each having an inclined trackway leading from the bottom to the top of the furnace, switch means in circuit with said motor, and adapted to be actuated as each car is moved upwardly along the trackway for connecting the motor with the source of supply, a timer, and means responsive to the operation of the timer for disconnecting the motor from its source of current supply, said last-mentioned means being actuated after one car has been dumped but before the other car has been raised to a point where the motor circuit is closed, said timer operating to effect rotation of the hopper continuously during the dumping of each skip load and at sufficient speed that at the completion of each dumping of a skip car, the material in the rotating hopper is substantially level.

10. A method of charging a blast furnace, wherein materials to be fed into the furnace are delivered to the top of it in skip carload lots and are dumped into a hopper which is closed at the bottom by a movable bell, and wherein the time required for dumping any skip carload varies with the nature and physical conditions of the material, comprising, rotating the hopper at a speed of substantially one revolution during the time required for the fastest dumping operation of all of the materials to be fed into the furnace, whereby at the completion of each dumping of the skip car the material in the rotating hopper is substantially level, maintaining the rotation during the time required for dumping a skip load, and holding the hopper stationary while the movable bell is being lowered for emptying the contents of the hopper.

11. A method of charging a blast furnace wherein materials to be fed into the furnace are delivered to the top of it in skip carload lots and are dumped into a hopper which is closed at the bottom by a movable bell, there being two cars for each furnace and so arranged that an empty car is moving downwardly while a loaded car is moving upwardly, comprising, rotating the hop-

per and its associated bell as a unit continuously during the entire dumping operation and at such speed that the hopper makes at least one revolution during the time required for the fastest dumping operation, whereby at the completion of each dumping of a skip car, the material in the rotating hopper is substantially level, initiating the rotation of the hopper sufficiently far in advance of the arrival of any car at the top of the furnace that the hopper may be accelerated to a uniform rate of speed by the time that the dumping operation commences, maintaining the rotation of the hopper during the dumping of each skip car, and then stopping the rotation until the other loaded car arrives at a predetermined point adjacent the top of the furnace. 15

12. A method of charging a blast furnace wherein materials to be fed into the furnace are delivered to the top of the furnace in skipload portions and are dumped into a hopper which is closed at the bottom by upward movement of a bell, which comprises rotating the hopper and associated bell continuously during the entire operation of discharging each skipload into the hopper, the rotation being at a rate sufficiently rapid to make at least one complete revolution during the dumping of each skipload, and to effect substantially level distribution of the material in the hopper. 20

13. In the method of charging a blast furnace closed at the top by a relatively large and a relatively small bell and hopper type of closure, the small hopper being disposed above the large hopper, in which method materials to be fed into the furnace are delivered to the top of the furnace in skipload portions, each such portion being dumped into the upper hopper from which it is separately discharged into the lower hopper by lowering the small bell, thereby progressively building up in the lower hopper a charge of materials for ultimate discharge into the blast furnace upon lowering the large bell, the improvements which consist in rotating the upper hopper and associated small bell continuously during the entire operation of discharging each skipload of material into the upper hopper at a rate of rotation sufficiently rapid to effect substantially at least one complete revolution during the entire dumping operation and to effect substantially level distribution of the material in said upper hopper, and successively delivering such substantially level portions of material to the lower hopper, whereby the latter is provided with a charge, which is substantially level. 50

14. A blast furnace having in combination, an annular liquid reservoir at the top thereof, a skip car for charging the furnace, a charge receiving hopper mounted for rotation on the furnace and having a cylindrical sleeve extending substantially the length of the hopper and disposed within the reservoir and terminating short of the bottom thereof, said sleeve cooperating with the walls of the reservoir to provide a tortuous path for the flow of liquid out of the reservoir incident to the pressure which may be exerted upon the liquid by gas tending to escape from the furnace, and means for rotating said hopper at least one complete revolution during a charge receiving interval, whereby at the completion of each dumping of the skip car, the material in the rotating hopper is substantially level. 70

15. In combination, a blast furnace, a skip car therefor, a charge-receiving hopper mounted for rotation at the top of the furnace, a bell operable to close the hopper, an electric motor for rotating the hopper and means for connecting the motor to the hopper to effect at least one revolution of the hopper during the charging operation, whereby at the completion of each dumping of a skip car, the material in the rotating hopper is substantially level. 5

16. In combination, a blast furnace having a liquid reservoir open to the atmosphere at the top thereof, a skip car therefor, a hopper rotatably mounted at the top of the furnace, a bell movable upwardly for closing said hopper, said hopper having a smooth-walled interior, and having a sleeve depending therefrom into the reservoir but terminating short of the bottom thereof, and providing a partition, one side of which is adapted to be in communication with the interior of the furnace and the other side of which is adapted to be in communication with the atmosphere, whereby gas escaping from the furnace is forced to flow in a tortuous path downwardly on one side of the partition, and then upwardly on the other side of the partition, and means for rotating said hopper continuously and at least one revolution while material for charging the furnace is being dumped into it, whereby at the completion of each dumping of the skip car, the material in the rotating hopper is substantially level. 25

17. In combination, a blast furnace, a skip car therefor, said furnace having a stationary hopper at the top thereof, a first bell providing a bottom closure for said stationary hopper, a hopper rotatably mounted on and above said stationary hopper, a second bell providing a bottom closure for the upper hopper, said upper hopper being adapted to receive a load of charging material while the second bell is in closed position and to discharge its contents into the stationary hopper upon lowering of the second bell while the bell of the stationary hopper is in closed position, means for rotating said upper hopper and said second bell continuously while said upper hopper is receiving a load of charging material and at a rate equal to at least one complete revolution during the dumping operation, whereby at the completion of each dumping of the skip car, the material in the rotating hopper is substantially level, and a seal disposed between the upper hopper and the stationary hopper to prevent the escape of gas from the latter during the time in which the bell of the stationary hopper is lowered for discharging the contents of the latter into the furnace. 45 55
